Primary Examiner — Marianne N Pandozzi*(74) Attorney, Agent, or Firm* — Cantor Colburn LLP(57) CLAIM

The ornamental design for a coffee carafe, as shown and described.

DESCRIPTION

FIG. 1 is a perspective view of a coffee carafe showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded perspective view thereof.

The broken lines are for environmental purpose only and form no part of the claimed design.
